United States Patent Office

Des. 182,965
Patented June 3, 1958

182,965

TABLE

Robert E. Kjer Jakobsen, Manhattan Beach, Calif., assignor to Virtue Bros. Mfg. Co., Los Angeles, Calif., a corporation of California

Application October 28, 1957, Serial No. 48,261

Term of patent 14 years

(Cl. D33—14)

Fig. 1 is a perspective view of a table, showing my new design.

Fig. 2 is an enlarged and fragmentary elevational view of a corner and leg of said table, showing in detail dominant features of the design.

Fig. 3 is a similarly enlarged elevational view of the lower end of one of the table legs.

The dominant features of the design are shown in the drawing in full lines.

The ornamental detail of the rail as shown in Fig. 2 is schematically shown in Fig. 1 and is continuous around the periphery of the table.

The leg not shown in Fig. 1 is like the legs shown and is disposed in the same relative position at the corner.

I claim:

The ornamental design for a table, substantially as shown and described.
